UNITED STATES PATENT OFFICE.

JOSEPH COLDWELL, OF SOUTH SWANSEA, MASSACHUSETTS.

THREAD-GUIDE FOR SPINNING-MACHINES.

1,134,315.

Specification of Letters Patent.

Patented Apr. 6, 1915.

Application filed September 9, 1914. Serial No. 860,828.

To all whom it may concern:

Be it known that I, JOSEPH COLDWELL, a citizen of the United States, residing at South Swansea, in the county of Bristol and State of Massachusetts, have invented a Thread-Guide for Spinning-Machines, of which the following is a specification.

The primary object of my invention is to provide a peculiar form of thread-guide for use in spinning what is commonly known as "novelty yarn", in which one of the threads in addition to being twisted on the other is wound thereon at predetermined intervals in bunches to form on the yarn what is usually termed "seeds". This particular kind of yarn is produced in the conventional type of ring-frame spinning machines by feeding one of the threads to the bobbin intermittently and the other continuously, whereby the continuously-run thread will be wound about the other or ground thread during the time the latter remains stationary, and of course the size of the bunch or seed is determined by the length of time the ground thread remains stationary. In some instances the operation of bunching or forming the seed is produced by passing the ground thread through the ordinary round-wire guide-eye and leading the continuously-run thread on to the same immediately below said eye, but by this arrangement the threads are liable to become tangled, and, furthermore, the winding or bunching is not close or compact.

It is the purpose of my invention, therefore, to provide a thread-guide for machines for spinning novelty yarn in which both threads are guided separately and independently to the point where the continuously-run thread is twisted and wound upon the intermittently-run or ground thread to thereby eliminate all danger of tangling; and a further purpose is to so construct and arrange the guide-eyes, in connection with a guide-member that the filling thread will be wound tightly on the ground thread to produce a compact bunch or seed.

Other objects and advantages of my invention will hereinafter appear, and what I claim as new, and desire to protect by Letters-Patent, is specifically set forth in the appended claims.

In the accompanying drawings, which form a part of this specification: Figure 1 is a view illustrating the application of my

invention, only those parts of a spinning machine being shown as required to indicate such application. Fig. 2 is an elevation of my improved thread-guide, and its support, looking at one side of the same. Fig. 3 is a similar view, looking at the other side of the thread-guide. Fig. 4 is a perspective view in detail.

Like numerals of reference indicate like parts in all the figures of the drawings.

Inasmuch as my invention relating to thread-guides is applicable to the ordinary type of ring-frame spinning-machine employed for spinning novelty yarn, it will be understood by those skilled in the art that the two threads which are twisted together between the guide-eye and the bobbin are fed from between the usual rolls (not shown), arranged in pairs, one for each thread; that pair feeding the ground thread, as 5, being run intermittently to stop or hold the thread at intervals, and the other pair of rolls which feed the other thread, as 6, run continuously; whereby when the ground thread is running with its companion thread they will be twisted together, as indicated at 7, and when the ground thread is held stationary the other, or continuously-run thread, will wind thereon immediately below the eye to form a bunch or seed 8, the twisting and winding being effected by the operation of the revolving bobbin, 9.

In carrying out my invention the thread-guide is constructed to form two eyes, 10 and 11, located practically side by side, and through said eyes pass the two threads 5 and 6, respectively, from the guide-bar 16 and feed-rollers. Directly below the eyes, and extending substantially on a vertical line therewith, is an arm or guide-member 12, disposed between the threads; that is to say, the thread 5 passes directly from the eye 10 over the front side of said arm and the thread 6 passes from the eye 11 over the rear side thereof, so that the twisting operation of the threads takes place between this arm or guide-member and the bobbin, and the winding of the thread 6 upon the thread 5, to form the seed, takes place at the lower edge of the said arm or guide-member. In the present instance the arm or guide-member 12 is half-round in cross-section, so as to present a tapering lower edge, whereby the winding operation will be effected close up.

or directly against the edge, insuring a tight bunching or winding and consequently a more compact seed.

In order to guide the thread 5 to the eye 10 I may, and preferably do, provide an arm 13, disposed above said eye, and for the purpose of guiding the thread 6 to the eye 11 there is a vertical guide-member 14 at one side of said eye above the plane of 10 the same and terminating at its upper end in a loop 14^a. It will be noted that the guide-member 14, 14^a, is located beyond and slightly to the rear of the eye 11, so that the thread 6 will be held a sufficient distance 15 away from the thread 5, between the guide-bar 16 and eyes to prevent them from coming together, before passing through the thread-guides the loop 14^a preventing disengagement of the thread 6 from the vertical portion of the guide-member.

The eyes and guide-members hereinbefore described may be constructed in any suitable manner, but are cheaply and conveniently made of wire, as herein shown, by 25 bending a single piece of wire upon itself, then forming the opposite eyes 10 and 11 at a suitable distance from the bend to leave an attaching shank, as 15, extending one terminal, as 13, from the eye 11 above the eye 10, to form the guide-member for the thread 5, and extending the other terminal from the eye 10 below the eye 11, to form the arm 12, and on to form the guide-member 30 14 with its loop 14^a. Half-round wire is used and bent so that the flat sides will come together in forming the round shank 35 15, and, as will be noted, will present the curved side as the surfaces over which the threads pass through the guide, with respect 40 to the eyes 10, 11, and the guide-members 12, 13, and 14, 14^a, as well as provide the desired tapered lower edge for the arm or guide-member 12.

The operation of my improved thread-guide will be readily understood from the foregoing description, in connection with the drawings, and it will be apparent that in order to provide novelty yarn having seeds of different colors two or more of the 45 thread-guides would be employed and disposed one above another so that the intermittently-run ground thread would pass through the eyes 10, and the continuously-run or filling threads of different colors run 50 through the eyes 11 separately; the filling thread to the uppermost guide being twisted and wound upon the ground thread alone, the filling thread to the second guide twisted and wound upon the yarn formed by said 55 first guide, and so on.

Having described my invention, I claim:

1. A thread-guide for spinning machines, comprising separate eyes for the threads, one of said eyes having an arm or guide-

member located below said eyes and at opposite sides of which the threads pass.

2. A thread-guide for spinning machines, comprising an arm or guide-member having a tapered lower edge, and means for guiding the threads to opposite sides of said arm, 70 for the purpose set forth.

3. A thread-guide for spinning-machines, comprising a pair of eyes located side by side, and an arm or guide-member located below said eyes and having a tapered lower 75 edge, the threads passing at opposite sides of said arm or guide-member, for the purpose set forth.

4. A thread-guide for spinning machines, comprising a pair of eyes located side by side, one of said eyes having an arm or guide-member located below said eyes and at opposite sides of which the threads pass from the eyes, and means for guiding the threads to the eyes.

5. A thread-guide for spinning machines, comprising a pair of eyes located side by side, an arm or guide-member located below said eyes, a substantially horizontal guide member above one of the eyes, and a guide-member for the other eye located above and at one side of the same.

6. A thread-guide for spinning machines, comprising a pair of eyes located side by side, an arm or guide-member located below said eyes, a substantially horizontal guide-member above one of the eyes, and a vertical guide-member above and at one side of the other eye, said vertical guide-member terminating at its upper end in a loop.

7. As an improved article of manufacture, a thread-guide for spinning machines, formed from a single piece of wire bent upon itself to provide a shank, the two portions being then bent in opposite directions 105 to form eyes, and the terminals extended beyond the eyes, respectively, to provide guide-members above and below said eyes.

8. As an improved article of manufacture, a thread-guide for spinning machines, formed from a single piece of wire bent upon itself and brought together to form a shank, eyes formed by bending the two portions of the wire in opposite directions, one of the terminals being extended from one of the eyes above the companion eye to provide a guide for the thread leading thereto, and the other terminal extended from the other eye below its companion eye and on to form a vertical guide-member terminating in a loop, substantially as shown and for the purpose set forth.

9. As an improved article of manufacture, a thread-guide for spinning machines, made of a single piece of half-round wire bent upon itself and brought together to form a round shank, the two portions of the wire bent upon themselves in opposite directions 125

to form eyes disposed side by side, and the terminal portion of one of the eyes extended below the eyes to provide a guide-member having a tapered lower edge, substantially 5 as herein shown and described.

In testimony whereof I have signed my

name to this specification in the presence of two subscribing witnesses.

JOSEPH COLDWELL.
